pany, Inc., a corporation of Delaware

Application October 28, 1942, Serial No. 463,645

7 Claims. (Cl. 201—51)

1

This invention relates to electrical apparatus, and more in particular to the construction and operation of electrical equipment such, for example, as an electric regulator in a power system.

An object of this invention is to provide an electric regulator which is sturdy in construction and reliable in operation and which is light in weight and inexpensive to manufacture. A further object is to provide an electro-magnetic construction which is economical to manufacture, efficient and dependable in operation, and adaptable to various conditions which arise. A still further object is to provide apparatus of the above character wherein efficient use is made of all of the materials of which the apparatus is constructed and wherein all of the various individual mechanical assemblies are of uniformly high efficiency and are durable. A further object is to provide apparatus of the above character wherein a standardized construction can be utilized under a variety of different conditions of operation. A further object is to provide such apparatus which is easily adjustable, and which will remain in adjustment without constant attention. These and other objects will be in part obvious, and in part pointed out below.

The invention accordingly consists in the features of construction, combinations of elements, and arrangements of parts as will be exemplified in the structure to be hereinafter described, and the scope of the application of which will be indicated in the following claims.

In the drawings:

Figure 1 is a front elevation of an electric regulator constituting one embodiment of the invention;

Figure 2 is a sectional view of certain of the apparatus shown in Figure 1 and is along the line 2—2 of Figure 3;

Figure 3 is a side elevation from the right of Figure 1;

Figure 4 is a top plan view;

Figure 5 is a showing of the stampings which are used to construct the magnetic parts of the apparatus;

Figure 6 is a sectional view of the assembled electro-magnet construction; and,

Figure 7 is a view of the electro-magnet and armature construction with certain parts broken away.

In the illustrative embodiment of this invention, an electric regulator is provided which includes; a carbon pile the electrical resistance of which is varied in order to obtain the control effect, illustratively shown herein with the resist-

2

ance increasing as the pressure on the carbon pile is decreased; an electro-magnet assembly having a rocking armature which is rocked from its initial position due to the effect of the magnetic field to increase the resistance of the carbon pile; a dashpot assembly to cushion the rocking operation and limit the speed at which the resistance is changed; a compensating spring assembly the effect of which varies as the spring is extended and which opposes the action of the magnetic field in rocking the armature; a thermo-responsive unit in the form of a bi-metallic strip which varies the tension of the compensating spring assembly in accordance with the ambient temperature; and a carbon pile compression adjustment means which maintains a substantially constant compressing force upon the carbon pile until there is a predetermined movement of the armature from its initial position whereupon the compressive adjustment means is rendered ineffective, and further movement of the armature effects a change in the resistance of the carbon pile.

Referring particularly to Figure 2 of the drawings, the regulator is attached to a panel 2 through two legs 4 and two legs 5 (see Figure 4) by screws 6, (Figure 2) one of which is threaded into each leg with its head countersunk in the panel. Legs 4 are integral with the left-hand vertical arm 8 of a frame construction 9 having a general U-shaped configuration and including a bottom transverse web 10 and a right-hand vertical arm 12. Legs 5 (Figure 4) are integral with an angle bracket 7 which is parallel to transverse web 10 of frame 9 and is rigidly held thereto in a manner explained more fully below. Bracket 7 has a vertical portion extending between the two legs 5 and a horizontal portion which is enlarged and apertured at its center. Rigidly secured in this aperture is a ball-bearing unit 15. Web 10 (Figure 2) is similarly enlarged and apertured and carries a similar ball-bearing unit 13. These two ball-bearing units provide a rockable mounting for a crank shaft 14 and rigidly mounted upon shaft 14 between the ball-bearing units is an armature 16 which is pressed onto the shaft.

Crank shaft 14 also has rigidly mounted upon it a crank assembly shown at the bottom of Figure 1 and designated generally at 18. Crank assembly 18 includes a dashpot arm 20 extending to the right and connected to the piston rod 22 of a dashpot 25. Dashpot 25 has a graphite piston 24 connected to the piston rod, and a cylinder 26 rigidly mounted at its upper end on a shelf

bracket 39 extending from the vertical arm 12 of frame 9. This mounting is provided by a stud 28 integral with the top of the cylinder and extending through the bracket and is clamped thereto by nut 32. The damping effect of dashpot 25 is regulated by adjusting a screw 34 (Figure 2) which controls the air outlet from cylinder 26.

The carbon pile, the resistance of which is varied in order to exert the control effect, extends vertically at the center of Figure 1 and is designated 36. At the top of carbon pile 36 is a contactor 37, above which is an insulator 38 and an anvil 43 pivotally suspended by a pin 42 from a pile lever 44. At the bottom of carbon pile 36 is a similar arrangement in the form of a contactor 39, an insulating member 41, and an anvil 43 pivotally carried by a pile pin 45 mounted eccentrically on the crank assembly 18 and secured by a nut 47. Referring again to the top of the carbon pile assembly, pile lever 44 is pivoted at its left end on a pin 48 carried by a bracket 46 integral with arm 8 of frame 9. At the right, pile lever 44 has a slot 54 into which is hooked the upper end of a tension pile spring 56. An adjusting screw 50 is threaded through the lever and is locked in adjusted position by a lock nut 52. The lower end of adjusting screw 50 is positioned above and adapted to engage the top of a stop pin 58 which has an enlarged lower end 59 threaded through a bracket 60 and locked in adjusted position by a lock nut 62. The threading on the enlarged portion 59 of stop pin 58 extends above the lock nut 62 and provides an anchor portion 63 upon which is threaded the tightly coiled small diameter lower end of the pile spring 56. This stop pin and pile spring assembly provides a tension control adjustment which acts through pile lever 44 to maintain an initial predetermined pressure on the carbon pile all in a manner to be more fully discussed below.

Crank assembly 18 is provided at the left with a segment portion 74 which has a hole 76 therein, in which is hooked the lower end of a tension spring 78. The upper end of tension spring 78 is coiled tightly and threaded onto the lower end of a threaded anchor pin 80. The predetermined adjustment of spring 78 on anchor pin 80 is maintained by a pair of lock nuts 82 and 84. As shown best in Figure 2, anchor pin 80 extends upwardly through an enlarged opening 86 in the horizontal portion of bracket 46, and, at the upper end, pin 80 carries a nut 90 which holds a knife-edged washer 88 in adjusted position. The knife-edged portion 88 of washer 88 rests in a groove 92 in the free end of an arched bi-metallic strip 94 which has a hole therethrough, through which pin 80 extends.

Bi-metallic strip 94 is rigidly mounted at its right-hand end by a pair of screws 96 (see also Figure 4) which are threaded into a horizontal bracket portion 98 (Figure 2) of the frame 9, and which hold a locking plate 100 tightly against the top of the bi-metallic strip. Bracket portion 98, strip 94, and plate 100 are recessed between screws 96 to allow for the adjustment of screw 34. Bi-metallic strip 94 is curved as shown best in Figure 2 with a main arch portion and a smaller inverted arch portion, and (see Figure 4) it is tapered from its fixed end toward its free end. This bi-metallic strip is effective to move anchor pin 80 up and down with changes in ambient temperature to thus change the tension on tension spring 78 and maintain the operating characteristics of the regulator constant.

As indicated above, armature 16 is rocked by the action of a magnetic field which opposes the action of spring 78. This magnetic field is produced by an electro-magnet 102 rigidly mounted (see Figure 2) upon the two arms 8 and 12 of the frame 9, and best shown in Figures 6 and 7. This electro-magnet is provided with a solenoid 103 and a core 104, which has a left-hand pole piece 105 and a right-hand pole piece 106 (see Figure 7). Pole pieces 105 and 106 have cylindrical pole faces with the same axis as the shaft 14 about which armature 16 rocks. Armature 16 is provided with pole tips 107 and 109, and the pole faces are cylindrical and concentric with the pole faces of pole pieces 105 and 106. Thus, the air gaps at the two ends of the armature are small and are of uniform length throughout the entire swinging movement of armature 16. However, many of the advantages of this invention can be realized when eccentric pole pieces are used, thus giving air gaps which are not uniform throughout.

Core 104 is built up of a plurality of similar laminations of the shape shown in Figure 5 at 108. Each lamination has therein four holes 110 which, when the laminations are stacked to form the core, are in alignment (see Figure 6), and the core is held together by sleeves 112 extending through those holes with a pair of ferrules 114 held upon the flanged ends of each sleeve. The outwardly extending end faces 113 of the four ferrules on each side of the core are ground after assembly to a single plane, and the spacing between the two planes on the opposite sides of the core is accurately controlled to a specified dimension. These two planes are normal to the axis of sleeves 112, and have a predetermined relationship with respect to pole pieces 105 and 106. Sleeves 112 and ferrules 114 are used to mount the core on the frame 9 with a stud 118 extending through each sleeve and secured to a hole in frame 9. The central portion of each stud is of reduced diameter to provide a clearance 120 about the stud at the center of sleeve 112 and a tight fit at the two ends of the sleeve. Referring again to Figure 2, the ends of the four studs 118 are held in the mounting holes in the two side arms of frame 9 by nuts 122 (see also Figure 3), and the other ends of the studs are held by similar nuts 124. The lower stud in the frame arms and the upper stud adjacent panel 2 extend through eyes in bracket 7 (Figure 4) which, as indicated above, carries the ball-bearing unit 15 and thus helps support the crank shaft. These studs 118 and their nuts 122 and 124 thus hold bracket 7 tightly against the end faces 113 on the core, and also press the opposite end faces 113 tightly against the machined surfaces of frame 9. Thus, the core 104 and bracket 7 are accurately and rigidly secured to frame 9. In this way, core 104 acts as a spacing and aligning means, and armature 16 is accurately held in place and in alignment with respect to the pole faces of pole pieces 105 and 106.

As indicated above, crank assembly 18 and armature 16 are biased clockwise (Figure 2) by a spring 78 toward the initial position shown wherein lever 20 of the crank assembly engages the top of an adjusting screw 128. Screw 128 is threaded through a bracket 130 integral with frame 9 and is held in adjustment by a lock nut 132'. The counterclockwise movement of lever 20, and thus of armature 16, is limited by the engagement of the lever with bracket 63. During operation, armature 16 takes a position between the full line and broken line positions

shown in Figure 7 wherein the moment of the force exerted by spring 78 in one direction balances the opposed moment of the force exerted by the electro-magnet.

As shown best in Figure 1 in this embodiment, the lower end of spring 78 is hooked in hole 76 in the crank assembly below the radius line perpendicular to the spring, and as the crank assembly swings counterclockwise, hole 76, and thus the lower end of the spring, moves to the right with a resulting shortening of the effective lever arm through which spring 78 acts. This shortening of the effective lever arm is such as to cause the moment of the force exerted by spring 78 to have the proper value at all times to permit the use of a constant air gap. Under some circumstances, it may be desirable to provide a variable air gap and an increasing effective lever arm through which the spring acts. Under these circumstances, a hole such as 76 is provided near the top of the cam portion 74 of the crank assembly, and a shortened spring 78 is hooked therein.

Referring to Figure 1, the center of pile pin 45 is directly above the center of shaft 14 so that the counterclockwise movement of the crank assembly swings anvil 43 to the left and downwardly. In the initial position of the elements, spring 56 maintains a constant compressive force on carbon pile 36, and the carbon pile holds anvil 40 and lever 44 elevated as shown so that the lower end of adjusting screw 50 is spaced from the top of stop pin 58. Thus, during the initial movement of the crank assembly and anvil 43, the entire carbon pile and anvil 40 move with anvil 43 with spring 56 exerting a "follow-up" force downwardly through lever 44 with the result that the carbon pile remains compressed. However, after a predetermined swinging movement of lever 44, adjusting screw 50 engages the top of stop pin 58, and this prevents further downward or "follow-up" movement of lever 44 and anvil 40. As a result, the further movement of anvil 43 by the counter-clockwise swinging of crank assembly 18, increases the distance between anvils 43 and 40, with a corresponding decrease in the compressive force exerted on the carbon pile. This causes the electrical resistance of the carbon pile to increase in the manner referred to above.

When the armature starts to swing from the full line initial position of Figure 7, the path of the flux is from the extreme tip of pole piece 108 through the armature and to the upper portion of pole piece 105. As the flux increases and the armature swings counterclockwise, the major portion of the flux still passes through the lower portion of pole piece 106, whereas the flux passes only through the upper portion of pole piece 105. Accordingly, pole piece 106 is larger than pole piece 105, and the entire core carries the flux efficiently at all times.

During manufacture, the laminations 108 of core 104 are stacked and fastened together by sleeves 112 and ferrules 114, in the manner discussed above, and solenoid 103 is wound directly onto this core. This type of winding is possible because the pole pieces 105 and 106 are spaced apart so that the cross member of the core which connects the two arms is "open" in a radial direction. Thus, the core is mounted to rotate about the center of its cross member with suitable insulating material in place, and the core is then rotated and the wire is wound to form the solenoid.

Armature 16 is built up of individual laminations 148 in the same manner as is core 104, and

these laminations are tightly pressed onto shaft 14. Referring to Figure 5, laminations 108 and 148 are stamped from a sheet of iron in a single operation. The iron from which these laminations are stamped has "directional characteristics" in the sense that the magnetic characteristics along the sheet of iron are superior in the direction of the "grain of the iron," that is, in the direction in which the sheet was rolled during manufacture. The sheet of iron illustrated was rolled in the direction from top to bottom so that the grain and the superior magnetic characteristics are between the top edge and the lower edge. Accordingly, the laminations 108 and 148 are stamped as shown, and laminations 148 and the two arms of lamination 108 have superior magnetic characteristics in the direction in which the lines of magnetic flux are set up, that is, along their longitudinal dimensions. Referring to Figure 7, armature 16 and the arms of core 104 have these superior characteristics so that the flux lines which are set up by solenoid 103 extend from the ends of the solenoid straight down the two arms of the core and thence across the armature, and all of this path is with the grain of the iron. The only portion of the magnetic circuit which does not have the superior magnetic characteristics is the connecting portion of core 104 which is surrounded by and under the direct influence of solenoid 103, the source of the magnetic flux. Thus, efficient use is made of the iron.

An additional feature aiding in providing an efficient unit is the provision of the core 104, built up of the U-shaped laminations 108, combined with the provision of minimum air gaps between core 104 and armature 16. Thus, the magnetic structure has no air gaps in its stationary parts and the two gaps between pole pieces 105 and 106 and armature 16 are only large enough for mechanical clearance during movement of the armature. The variable balancing feature and the adjusting and control features of the regulator make it possible to provide this magnetic structure without sacrificing the efficiency and reliability of the action.

The electrical connections to the regulator are provided, as shown best in Figure 3, through four terminals 133, 134, 140, and 146 mounted on panel 2 with a pair of leads 131 and 132 connecting solenoid 102 to terminals 134 and 133, and with a pair of leads 138 and 144 connecting connector plates 37 and 39 to terminal plates 140 and 146, respectively. In practice, solenoid 102 carries a current which varies in accordance with the control effect to be exerted, and the current through the carbon pile is then varied by the regulator with the result that the proper control effect is exerted at all times.

The pile spring 56 (Figure 1) maintains constant pressure upon the carbon pile except when this pressure is relieved by the engaging of adjusting screw 50 with stop pin 58. Thus, even though the length of the carbon pile changes during use, the spring 56 maintains constant pressure on the carbon pile. Adjusting screw 50 is readily changed to vary the amount of initial movement of the armature during which no control effect is exerted. The changes in ambient temperature are corrected for by the bi-metallic strip 94 which moves anchor pin 80 up and down, and thereby changes the tension on spring 78. The tension characteristics of the spring is changed by changing the number of turns which are threaded onto the end of the anchor pin; that is, when the number of turns threaded onto the

anchor pin is increased, the number of turns active as a spring is correspondingly decreased.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a carbon-pile regulator, the combination of, a U-shaped frame constituting a rigid mounting means and having two leg portions connected together at their lower ends by a base portion and having their free ends extending upwardly, an inverted U-shaped magnetic core having two legs extending along and rigidly clamped to the respective leg portions of said frame with the lower free ends of the legs substantially at the base of the frame and with the base portion of the core being positioned along the side of the leg portions of the frame, a bi-metallic strip extending across the top of said frame with one end rigidly attached to the top of one of said leg portions, a tension spring assembly suspended from the other end of said strip and extending downwardly toward the base portion of said frame, a rotor assembly mounted at the base portion of said frame and adapted to be turned by variations in the magnetic field of said core to exert a motive force which varies in accordance with the control effect to be exerted, a carbon-pile assembly carried by said frame and positioned longitudinally thereof with its lower end adapted to be moved upwardly to compress the carbon pile in accordance with the control effect desired, and means connecting said tension spring assembly to oppose the action of said motor assembly.

2. Apparatus as described in claim 1 wherein a dashpot is mounted on the side of said frame opposite said tension spring assembly and is connected to oppose rapid changes in the control effect.

3. Apparatus as described in claim 1 wherein the upper end of said carbon pile is held against a lever which is pivotally carried by one leg of said frame and which is biased against said carbon pile by a coil spring with adjustable stop means limiting the movement of said lever toward said carbon pile, said stop means including a stop rod which is rigidly carried by said frame, and said spring being coiled about and anchored to said rod.

4. Apparatus as described in claim 1 wherein said motor assembly is formed by an electro-magnet which rocks an armature with the magnetic parts of the electro-magnet being formed by a plurality of substantially identical laminations of iron in face to face relationship with each lamination forming a complete magnetic path from one end of said armature to the other end thereof.

5. In a carbon pile regulator, a carbon pile assembly, a base construction including means to hold said carbon pile assembly, adjustable biasing means to exert on said carbon pile assembly a predetermined compressive effect and including stop means to limit the action of said bias-

ing means, said biasing means comprising a coil spring and said stop means including a rigid longitudinal member extending through the center of said coil spring and having the fixed end of said coil spring attached to said longitudinal member.

6. In a carbon pile regulator, the combination of, a U-shaped frame construction having a pair of substantially parallel spaced longitudinal portions rigidly connected at the base of the U by a base portion, a substantially U-shaped electro-magnet rigidly mounted on said frame construction and having a pair of substantially parallel spaced longitudinal portions rigidly connected by a base portion, said electro-magnet being mounted on the frame construction with the respective longitudinal portions in side-by-side parallel relationship and with the base portions oppositely positioned with respect to each other whereby the free ends of the longitudinal portions of the electro-magnet are positioned at the base portion of the frame construction and having substantially cylindrical pole faces, a frame member of substantially the length of the base portion of said frame construction and positioned parallel to said base portion on the opposite side of said electro-magnet, means clamping said frame member to said frame construction whereby said electromagnet is clamped in place and acts as a spacing means to hold said frame member in spaced relationship, a pair of ball-bearing units respectively mounted on said frame member and the base portion of said frame construction with their axes in alignment on the axis of said cylindrical pole faces, an armature assembly having an armature positioned between said pole faces and having armature pole faces substantially concentric with said cylindrical pole faces and having shaft portions respectively extending through said ball-bearing units to provide a rocking support, a tension spring extending longitudinally of said frame construction with one end adjustably secured to the end of said frame construction opposite the base portion thereof and with the other end of said tension spring being attached to said armature assembly at a point beyond the rocking axis whereby a rocking movement of the armature assembly results in a reduction in the length of the lever arm through which the spring acts with the reduction being of sufficient amount to compensate for the increased pull of the extended spring, a rigid elongated stop member positioned substantially parallel to said longitudinal portions of the frame construction, and a coil spring freely coiled around said stop member with the coil spring fixed at one end of the stop member and attached at the other end to means mounted on said frame construction.

7. Apparatus as described in claim 6 which includes, a carbon pile assembly mounted on said frame construction and including a carbon pile which is positioned substantially parallel to and equidistant from said longitudinal portions of the frame construction, and means to change the compressive action on said carbon pile in accordance with the movement of said armature.

LOUIS H. VON OHLSEN.
